GAS LOG LIGHTER

Marvin L. Stark, Anchorage, and Frank C. Lewis, Louisville, Ky., assignors to Peerless Manufacturing Division, Dover Corporation, Louisville, Ky., a corporation of Kentucky

Filed May 28, 1964, Ser. No. 80,189

Term of patent 14 years

(Cl. D81—10)

FIG. 1

FIG. 2

FIG. 3

FIG. 4

FIG. 5

FIG. 6

FIG. 1 is a perspective view of a gas log lighter, showing our new design.

FIG. 2 is a top view of the gas log lighter shown in FIG. 1.

FIG. 3 is an end view of the gas log lighter taken from the left-hand side of FIG. 1.

FIG. 4 is an elevational view of the gas log lighter shown in FIG. 1.

FIG. 5 is an end view of the gas log lighter taken from the right-hand side of FIG. 1.

FIG. 6 is a bottom view of the gas log lighter shown in FIG. 1.

We claim:

The ornamental design for a gas log lighter, substantially as shown.
